(57) **CLAIM**

The ornamental design for an elevator car, as shown and described.

DESCRIPTION

The patent or application file contains at least one drawing executed in color. Copies of this patent or patent application publication with color drawing(s) will be provided by the Office upon request and payment of the necessary fee.

FIG. 1 is a perspective view of an elevator car showing our new design in an exemplary embodiment;

FIG. 2 is a rear view of the embodiment shown in FIG. 1; FIG. 3 is a front view of the embodiment shown in FIG. 1; FIG. 4 is a side view of the embodiment shown in FIG. 1; FIG. 5 is another side view of the embodiment shown in FIG. 1;

FIG. 6 is a top view of the embodiment shown in FIG. 1; FIG. 7 is a bottom view of the embodiment shown in FIG. 1;

FIG. 8 is a perspective view of an elevator car showing our new design in an exemplary embodiment;

FIG. 9 is a rear view of the embodiment shown in FIG. 8; FIG. 10 is a front view of the embodiment shown in FIG. 8; FIG. 11 is a side view of the embodiment shown in FIG. 8; FIG. 12 is another side view of the embodiment shown in FIG. 8;

FIG. 13 is a top view of the embodiment shown in FIG. 8; and,

FIG. 14 is a bottom view of the embodiment shown in FIG. 8.

The broken lines in the figures are for environmental purposes only and form no part of the claimed design.
